ATTORNEY

UNITED STATES PATENT OFFICE.

ABRAHAM H. GODKEVITCH, OF NEW YORK, N. Y.

WOODEN SHIPPING-CASE.

1,391,470.

Specification of Letters Patent. Patented Sept. 20, 1921.

Application filed March 31, 1921. Serial No. 457,202.

To all whom it may concern:

Be it known that I, ABRAHAM H. GODKEVITCH, a citizen of the Republic of Russia, and resident of New York, in the county 5 of New York and State of New York, have invented certain new and useful Improvements in Wooden Shipping-Cases, of which the following is a specification.

This invention is an improved case or box 10 adapted for use in the shipment of valuable goods such as silks, cigars, etc., the object of the invention being to so form and connect the walls that the case cannot be opened by removing or loosening the wall or 15 a board thereof without leaving tell-tale evidence that the case has been tampered with. The consignee, upon noting such evidence of tampering may refuse to receipt for the case as in good condition, and 20 may thus be protected from loss. The actual loss from theft will also be reduced to a minimum, if not entirely eliminated, as a person tempted to open the case and extract a portion of the contents while the case 25 is in transit, would hesitate to do so if he was fairly sure to be found out.

As one important feature of my construction I provide a novel form of automatic locking device, the parts of which automatically come into engagement upon the 30 closing of the lid, and which prevents the lid from being opened without breaking or destroying the same.

In the accompanying drawings I have 35 illustrated one form which my invention may assume. In this construction.

Figure 1 is a perspective view of a case, a portion being broken away to show one of the fastening devices,

40 Fig. 2 is a vertical section through the top, showing the fastening device in said elevation.

Figs. 3 and 4 are sections on the lines 3-3 and 4-4 respectively, of Fig. 2, and 45 viewed in the directions indicated by the arrows.

Fig. 5 is a section, on the line 5-5, of Fig. 1, and

50 Fig. 6 is a perspective view of one member of the fastening device.

My improved case in the form illustrated includes a top 10, bottom 11, ends 12 and sides 13 formed of wooden boards. The ends preferably include a rectangular frame 55 13, to the inner surface of which the end

boards are secured and the top, bottom and sides overlap this frame so that their ends are flush with the outer surface of the latter. The top and bottom have similar transverse boards or bars 14 extending 60 across the main boards of the top and bottom, and these bars 14 at their ends are secured to vertical bars or boards 15 on the side of the box. Preferably the bars 15 have recesses at their extremities receiving 65 the projections 16 so that adjoining ends of the bars 14 and 15 may be connected by both vertical and horizontal nails.

Within the box and adjacent to each end of each of the cross bars 14, I provide an automatic fastening device. This includes a plate 17 secured to the top by a bolt 18 and adapted to lie adjacent to the inner surface of the end wall 13. This plate 17 has a second plate 19 rigidly secured thereto and 70 spaced therefrom by rivets 20, two of which serve as pivots for catches 21. These latter extend downwardly between the two walls 17 and 18, and are pressed apart by a spring 22 of any suitable kind. The side wall 13 75 of the box carries a retainer in the form of a plate 22 of the form shown in Fig. 6. This has a lower end portion 23 adapted to be secured to the wall by a bolt 24. Above this portion 23 the plate bends outwardly from the wall to a distance slightly 80 greater than the thickness of the plate 17 and the parts carried thereby, and has a pair of flanges 25 extending toward and preferably to, the inner surface of the wall 85 13. These are spaced apart to a distance substantially equal to the width of the plates 17 and 19, so that the latter may enter between the flanges 25 and between the plate 22 and the wall 13. The spring pressed 90 catches 21 are pointed at their lower ends and have shoulders which may engage beneath the flanges 25, as shown in Fig. 2, after the cover has been forced downwardly 95 into position.

The two members of the retainer are so positioned that when the cover is placed on the box, the cover will be in proper registry with the walls and will be positively and permanently held down. The plates 17 and 100 22 are held to the walls each by a single bolt, and these are of such character that they cannot be unscrewed from the exterior. Preferably the heads are counter sunk or rounded and if desired, the extreme inner 105 110

ends of these bolts may be slightly riveted over, to prevent any possibility of the nuts thereon being loosened or removed. The bolts 18 and 24 extend through the bars 14 and 15, so that the four bars are positively connected at their ends and cannot be lifted or removed, and thus no one of the boards of the top, bottom or sides can be lifted off upon withdrawal of the usual nails. The bolts also prevent any sliding or endwise movement of the boards of the top, bottom and sides through which these bolts extend. To prevent the endwise sliding of any of the intermediate portions of the top, bottom or sides upon the removal of the nails therefrom, I preferably provide additional securing means in the form of pins carried by such intermediate portions, and at their ends and entering the end frames. For instance, in Fig. 5 I have shown these pins in the form of bolts 27 connected to the top by nuts against the under surface of the top, but the bolts extend a sufficient distance beyond the nuts so as to enter recesses or sockets in the end walls or the frame thereof. These bolts cannot be removed, nor access gained to the nuts thereof while the box is closed, and they prevent the sliding of the boards carrying the same. The intermediate portions of the bottom, top and sides may be effectively prevented from endwise sliding movement by nailing them to the bars 14 and 15 from the inner surface, so that the nails are concealed from view and cannot be withdrawn or driven out.

To prevent the intermediate boards of the end walls from being forced inwardly I preferably provide bars 28 extending across each end at right angles to the direction of the boards of the latter, and these may be bolted to the intermediate boards of the ends by bolts 29, the heads of which are of such character that the bolts cannot be rotated.

With the box constructed as above described and nailed together, the contents is effectively protected, and no one of the walls and no one of the boards of any wall can be loosened or removed to gain access to the interior without positively breaking the board and thus prevent its replacement in its original condition.

It will be noted that the bars 14 and 15 form a frame which encircles the case, and that this frame is secured together by the fastening device inside of the case. The bolts which hold the fastening device to the frame bars also prevent the endwise movement of the adjacent portions of the walls. It will of course be evident that the specific fastening devices shown need be employed only in connection with the cover, as the bar across the bottom may be secured to the end bars 15 by a plate corresponding to the plate

17, but directly secured to the adjacent side by a bolt similar to the bolt 24.

Having thus described my invention, what I claim as new and desire to secure by Letters Patent is:

1. A shipping case having bars extending transversely of the top, bottom and two opposite vertical walls upon the exterior thereof, a fastening device upon the interior of the case and connecting said bars together and including interengaging parts automatically locking to prevent removal of any one of said walls after the closing of the case.

2. A shipping case having bars extending transversely of the top, bottom and two opposite vertical walls upon the exterior thereof, spring catches connected to the opposite ends of one of said bars upon the interior of the case and retainers secured to the adjacent ends of the bars on adjoining sides and adapted to engage with said catches to prevent opening of the case.

3. A shipping case having bars extending transversely of the top, bottom and two opposite vertical walls on the exterior thereof, fastening devices upon the interior of the case and connecting said bars together and including a plate carried by one wall and adapted to lie adjacent to the adjoining wall, a pair of oppositely acting spring pressed catches carried by said plates, and a retainer carried by said adjoining wall and adapted for interlocking engagement with said catches.

4. A fastening device for shipping cases including a plate secured to the interior surface of one wall and adapted to lie adjacent to and parallel with an adjoining wall, a plate secured to said adjoining wall and having portions spaced therefrom to receive said first mentioned plate therebetween, a pair of lugs on said second plate and projecting toward said second wall, and a pair of spring pressed catches carried by said first plate and adapted to enter between and lock beneath said lugs upon the closing of the case.

5. A shipping case having end frames, top bottom and side walls formed of boards overlapping and secured to said frames, bars extending transversely of said top, bottom and side walls, automatic devices upon the interior of the case and including coacting parts carried by said bars at the ends thereof for locking said bars together, and independent means for preventing endwise movement of the intermediate portions forming said top, bottom and side walls.

Signed at New York, in the county of New York and State of New York this 28th day of March, A. D. 1921.

ABRAHAM H. GODKEVITCH.
